Attorney

UNITED STATES PATENT OFFICE.

WILLIAM E. BLACKSTONE, OF BUCHTEL, OHIO.

PUMPING APPARATUS.

1,268,917.

Specification of Letters Patent. Patented June 11, 1918.

Application filed October 19, 1916. Serial No. 126,500.

To all whom it may concern:

Be it known that I, WILLIAM E. BLACKSTONE, a citizen of the United States, residing at Buchtel, county of Athens, and State of Ohio, have invented certain new and useful Improvements in Pumping Apparatus, of which the following is a specification.

My invention relates to pumping apparatus and particularly to such apparatus as is especially adapted for pumping out sumps or other pits in which water accumulates.

In operating mines it is customary to provide numerous sumps in which the water or moisture in the mine will accumulate and to provide suitable pumping apparatus for drawing off the water which accumulates.

The object of my invention is to provide an improved pumping apparatus for the purpose mentioned which shall automatically set the pump into operation when the water in any of the sumps has reached a predetermined level.

A further object of my invention is to provide, in a device of the class mentioned, means whereby each sump will be cut off from the pump line when the water in the same has been practically exhausted.

A further object of my invention is to provide in a pumping device of the class mentioned means whereby the portion thereof at each sump may be adjusted to accommodate the same to the rate of flow of water into the sump. Other objects will appear hereinafter.

With these objects in view my invention consists generally in a motor driven pump connected to a pump-line and the motor controlled by a circuit equipped with a switch, a branch pipe leading from the pump line to each sump, a valve in each branch line, a float arranged in the respective sumps for operating the valve with the rise and fall of water in the sump and means controlled by the rise and fall of said float for opening and closing the circuit to the motor. My invention further consists in various details of construction and arrangement of parts, all as will be fully described hereinafter, and particularly pointed out in the claims.

My invention will be more readily understood by reference to the accompanying drawings, forming a part of this specification, and in which—

Figure 1 is an elevation of my invention illustrating the motor driven pump and main pump line together with the details of

the portion of the device arranged at each sump,

Fig. 2 is a perspective view, partially broken away, of the valve and valve operating mechanism,

Fig. 3 is a vertical transverse section through the valve on substantially the line 3—3 of Fig. 1, and

Fig. 4 is a detail horizontal section on substantially the line 4—4 of Fig. 1.

Referring now to the drawings 1 indicates a pump of any ordinary or preferred form and 2 a motor for operating the same. Connected to the pump 1 is the main pump line or pipe 3 which is adapted to serve a plurality of branch pipes 4, each leading to a sump or pit 5. Only one sump and its respective pipe 4 is shown, as the general arrangement including a plurality of sumps is well known in the art.

Arranged at each sump is a valve casing 6 which may comprise a wooden block having a transverse horizontal bore 7 in which is arranged a rotatable valve 8 which may also be of wood. The valve casing 6 is provided with a longitudinally arranged bore 9 extending partially through the same and communicating with a downwardly extending bore 10. The end of the bore 9 is connected to the branch pipe 4 and the end of the portion 10 with a pipe 4' extending substantially to the bottom of the sump where it may be provided with a strainer 11, for obvious reasons. The valve 8 is provided with a transverse bore 12 which, when the valve is in one position, registers with the bore 9 and when the valve is in another position, closes the passageway through said bore and to the pipe 4. Fixed to the opposite ends of the valve member 8 is a pair of arms 13. These are rotatably fixed to the valve member as by pins 14 and the free ends of said arms extend considerably beyond the end of the valve casing 6 and are secured to a float block 15. The float block 15 is provided with a plurality of vertically disposed bores 16 which, in a large measure, prevent the block from becoming water soaked.

It is obvious that with the above construction, when the water in the sump rises, the float 15 will rise, and in rising, will open the valve 8; also that as the water is pumped out of the sump the float will drop thereby closing the valve. One of the objects of my

invention is to provide means whereby, as the water rises in the sump, the motor will be set into operation, and to this end I equip the electric circuit of the motor, which operates the pump, with a switch, or pair of contacts, at each sump whereby the rise and fall of the float in the sump will make or break the circuit to the motor; and so arranged that the device at each sump may 10 close the circuit to start the pump into operation. Referring to the drawings 17 and 18 indicate the lines of the circuit to the motor 2, and 19 the source of electric supply. Arranged at each sump is a jumper pole 20 provided with a suitable support permitting of vertical reciprocation of the pole. The pole is provided with a contact member 21 connected as at 22 with one line of the motor circuit and adjacent thereto is a 15 contact 23 which is connected as at 24 with the other line of the circuit. It is obvious that by moving the pole upwardly the contacts are brought into engagement therewith closing the circuit and starting the motor 20 driven pump. The lower end of the jumper pole 20 is preferably bifurcated as indicated at 25 and provided with a plurality of threaded apertures 26, the purpose of which will be presently described. Fixed to the 25 float 15 is an arm 27 which is preferably in the form of a loop as shown encircling one portion of the bifurcated end 25 of the jumper pole. 28 indicates a pin adapted to be arranged in the apertures 26 and this is 30 preferably in the form of a thumb screw as indicated clearly in Fig. 4. When the float rises the member 27 engages under the pin 28 and raises the jumper pole to bring the contacts 21 and 23 into engagement. When 35 the float drops it engages a transverse member and drops the jumper pole to disengage the contacts. To this end a second pin, 28', may be employed but I prefer to have the ends of the portions 25 connected by an 40 integral transverse portion 25' which prevents spreading of the bifurcated portion and also serves as a stop for the engagement with the member 27. A balance spring 45 29 is provided for the jumper pole, the tension of which is just sufficient to hold the contacts 21 and 23 in engagement after the pole is raised and which will not appreciably interfere with the downward movement of the pole due to the dropping of the float 15. 50 To prevent leakage of water between the valve and its casing I provide an annular gasket 30 at each end of the valve which is 55 preferably seated in a groove 31, formed in the valve end and adjacent portion of the casing and these gaskets are held in position by the adjacent ends of the arms 13 as shown clearly in Fig. 3.

From the foregoing description it will be clear that as soon as the water rises in any 60 sump in the mine the respective float will

rise and close the contacts 21 and 23 thereby starting the pump into operation. When the water has been pumped from this particular sump the contacts will be separated, as above described, but the circuit to the 70 motor will not be broken until the water in all of the sumps has been reduced to such an extent as to disengage all of the contacts. It should be noted that by providing the plurality of apertures 26, the pin 28 may be set 75 so as to bring the device into operation when the water has reached any desired level in any particular sump and this is advantageous owing to the fact that some sumps in a mine will fill more rapidly than others. It 80 should also be noted that the valve will open the branch line proportionately to the amount of water in the sump.

I claim:

1. In a device of the class described, a 85 motor, a pump driven thereby, in combination with a circuit for said motor, a line pipe for said pump, a branch suction pipe, a valve in the last mentioned pipe, a float connected to said valve and adapted to operate the 90 same, a circuit closer in said circuit and means actuated by said float for closing said circuit, substantially as described.

2. In a device of the class described, a 95 motor and a pump driven thereby in combination with a circuit for said motor and a line pipe for said pump, a branch suction pipe, a valve in the last mentioned pipe, an arm fixedly connected to said valve, a float on said arm, a circuit closer in said circuit and an operative connection between said float and said circuit closer, substantially as described.

3. In a device of the class described, a 105 motor and a pump driven thereby in combination with a circuit for said motor and a line pipe for said pump, a branch suction pipe, a valve in the last mentioned pipe, an arm fixedly connected to said valve, a float on said arm, a circuit closer for said circuit, an operative connection between said float and said circuit closer, and means for adjusting the connection between said float and said circuit closer, substantially as described.

4. In a device of the class described, a 110 motor and a pump operated thereby in combination with a circuit for said motor, a line pipe for said pump, a branch suction pipe, a valve in said last mentioned pipe, an arm fixedly connected to said valve, a float on 115 said arm, a vertically reciprocating member adjacent said float, a circuit closer for said circuit comprising a pair of contacts, one of said contacts being fixed and the other arranged on said vertically reciprocating member and co-operating means on said float and said member for raising and lowering the latter, substantially as described.

5. In a device of the class described, a 120 motor and a pump operated thereby in combi- 125

nation with a circuit for said motor, a line pipe for said pump, a branch suction pipe, a valve in said last mentioned pipe, an arm fixedly connected to said valve, a float on said arm, a vertically reciprocating member adjacent said float, a circuit closer for said circuit comprising a pair of contacts, one of said contacts being fixed and the other arranged on said vertically reciprocating member, an actuating member on said float, cooperating elements on said vertically reciprocating member for raising and lowering the latter, one of said elements being adjustable with relation to the other, substantially as described.

6. In a device of the class described, a motor and a pump operated thereby in combination with a circuit for said motor, a line pipe for said pump, a branch suction pipe, a valve in said last mentioned pipe, an arm fixedly connected to said valve, a float on said arm, a vertically reciprocating member adjacent said float, a circuit closer for said circuit comprising a pair of contacts, one of said contacts being fixed and the other arranged on said vertically reciprocating member, said reciprocating member being provided with a plurality of apertures, a pin selectively mounted in said apertures and means on said float for engaging said pin, substantially as described.

7. In a device of the class described, a motor and a pump actuated thereby in combination with a circuit for said motor, a line pipe for said pump, a branch suction pipe, a valve in the last mentioned pipe, an arm fixed to said valve, a float on said arm, a ver-

tically reciprocating member adjacent said float, a circuit closer for said circuit comprising a fixed contact and a contact member on said reciprocating member, means for balancing the weight of said member and an operative connection between said float and said member, substantially as described.

8. In a device of the class described, the combination with a pump and means for driving the same, of a line pipe for said pump, a branch suction pipe, a valve in the last mentioned pipe, an arm fixed to said valve, a float block fixed to said arm, said float block being provided with ventilating perforations and means actuated by the rise and fall of said float for starting and stopping said pump, substantially as described.

9. In a device of the class described, a plurality of liquid receiving recesses to be drained, in combination with a pump, a motor for actuating the pump, a circuit for said motor, a line pipe for said pump, a branch suction pipe to each of said liquid receiving recesses, a valve in each of said branch pipes, a float connected to said valve and adapted to operate the same, a circuit closer adjacent each of said valves and means actuated by either of said floats for closing the circuit to the motor, substantially as described.

In testimony whereof I have signed my name to this specification in the presence of two subscribing witnesses.

WILLIAM E. BLACKSTONE.
